[57] CLAIM

The ornamental design for a front cover for a microphone, as shown and described.

DESCRIPTION

FIG. 1 is a front, bottom and left side perspective view of a front cover for a microphone showing my new design;

FIG. 2 is a top plan view thereof;

FIG. 3 is a front elevational view thereof;

FIG. 4 is a bottom plan view thereof;

FIG. 5 is a left side elevational view thereof; and

FIG. 6 is a right side elevational view thereof.

The broken line showing of the rear portion of the microphone is for illustrative purposes only and forms no part of the claimed design.

FIG. 2

FIG. 1

FIG. 3

FIG. 4

FIG. 5

FIG. 6
